(57) **CLAIM**

The ornamental design for a laser sensor, as shown and described.

DESCRIPTION

The file of this patent contains at least one drawing executed in color. Copies of this patent with color drawings will be provided by the Office upon request and payment of the necessary fee.

FIG. 1 is an upper right front perspective view of a laser sensor showing my new design.

FIG. 2 is a lower left rear perspective view of the laser sensor of FIG. 1.

FIG. 3 is a front elevational view of the laser sensor of FIG. 1.

FIG. 4 is a rear elevational view of the laser sensor of FIG. 1.

FIG. 5 is a left side elevational view of the laser sensor of FIG. 1.

FIG. 6 is a right side elevational view of the laser sensor of FIG. 1.

FIG. 7 is a top plan view of the laser sensor of FIG. 1; and, FIG. 8 is a bottom plan view of the laser sensor of FIG. 1.
